United States Patent Office

Des. 183,545
Patented Sept. 16, 1958

183,545

COMBINED TABLE AND SEAT UNIT

Charles Shore, Cheltenham, Pa.

Application May 7, 1957, Serial No. 46,055

Term of patent 14 years

(Cl. D33—14)

I claim:

The ornamental design for a combined table and seat unit, substantially as shown.
